CLAIM

The ornamental design for a computer screen with icon, as shown and described.

DESCRIPTION

FIG. 1 is a front view of a computer screen with icon.

FIG. 2 is a perspective view of the computer screen with icon.

FIG. 3 is a second perspective view of the computer screen with icon; and,

FIG. 4 is another embodiment of the computer screen with icon.

The broken lines showing the computer screen and portions of the icon form no part of the claimed design.
